UNITED STATES PATENT OFFICE.

BERT R. EMRICK, OF NYAUNGHLA, UPPER BURMA, INDIA.

CASING SPEAR.

Application filed June 14, 1922. Serial No. 568,184.

To all whom it may concern:

Be it known that I, BERT R. EMRICK, a citizen of the United States, residing at Nyaunghla, Upper Burma, India, have invented certain new and useful Improvements in Casing Spears, of which the following is a specification.

This invention is for a casing spear of the kind used for withdrawing casings in well drilling operations.

A large number of different forms of casing spears are in use, but many of them frequently do not catch at the proper time, and are more or less of such delicate construction that the tripping mechanism is unreliable, with the result that the operator takes a great chance of not being able to free his spear in the event that it becomes necessary.

20 The present invention has for its primary objects the provision of a strong casing spear of relatively simple construction, which will be positive in its operation to either pipe gripping or pipe releasing position.

25 Other objects are to provide a spear which is more or less self-cleaning and which may be adapted for use in connection with rotary systems of drilling.

30 My invention may be readily understood by reference to the accompanying drawings, in which:

Fig. 1 is a side elevation of the casing spear, with the parts in open position;

35 Fig. 2 is a similar view showing the parts moved to gripping position;

Fig. 3 is a vertical section through Fig. 1;

40 Figs. 4, 5, 6 and 7 are transverse sections on the planes of lines IV—IV, V—V, VI—VI and VII—VII, respectively;

Fig. 8 is a view corresponding to Fig. 3, showing a slightly modified construction for use in rotary drilling operations.

In the drawings, A indicates the body of the spear, which body has a reduced, tapered, threaded end 5 of usual construction, and a squared portion 6 to which a wrench may be applied. At 7, the diameter of the body increases, providing a shoulder. Below the shoulder are a plurality of, preferably three, substantially flat faces 8 which are inclined away from the longitudinal axis of the body toward the lower or bottom end thereof. These faces are separated one from the other by peripheral portions 9 of the body. Designated as 10 are segment-shaped

shoulders which are formed above the flat inclined faces. In each of the faces 8 is a dove-tail slot 8^a.

The body of the spear below the faces 8 is materially reduced at 11, it extending downwardly from point 11 to the end of the spear as a cylindrical mandrel 12. The lower end of the mandrel is threaded at 13.

Surrounding the upper portion of the mandrel, and slidably thereon, is a collar 15 having an annular groove 16 in its periphery.

Slidably mounted on each face 8 of the body, is a casing-engaging and pulling wedge 17. These wedges, which are toothed transversely in order to enter into lifting engagement with a pipe or casing, have rounded faces to conform with the curvature of the spear and taper in width from the top downwardly to correspond to the decrease downwardly in the width of the faces 8. The wedges increase in thickness from the bottom toward the tops thereof, the slope of the inner faces of the wedges corresponding to the slope downwardly of faces 8. Consequently, the wedges move radially outwardly when they move upwardly thereof. Each wedge 17 has a dove-tail rib 17^a on its inner face to engage in groove 8^a of the face 8 on which the slip engages.

The upward movement of the slips is limited by shoulder 10. The lower end of each slip is provided with an inwardly turned transversely extending lug 17^b. These lugs are entered into groove 16 of collar 15. Thus, the slips may all move in unison with collar 15.

In the parts 9 of the body are reciprocable pins 18 slidably retained in position by screws 19, and yieldably urged downwardly by springs 20. The outer ends of these pins engage the collar 15 to urge the collar away from the shoulder at 11.

Slidable on the mandrel 12, below collar 15, is a second collar 21 which may be termed the bottom slip block. This block is provided with a plurality of, four being shown, longitudinally extending dove-tail grooves 22. These grooves increase in depth from the top toward the bottom, and loosely slidably in each groove is a lower slip 23. Slips 23 are smaller than slips 17, and are of suitable shape to be received in the dove-tail grooves 22. They increase in thickness from their tops toward their bottoms to correspond to the slope of the dove-tail grooves,

- so that when their tops are at the upper limits of grooves 22, their peripheries protrude beyond the periphery of the lower slip block, as shown in Fig. 2. The peripheries 5 of the lower slips are provided with transverse teeth which are reversed to the teeth on slips 17, so that they bite the pipe when the spear is urged downwardly, as herein-after described.
- 10 Screwed onto the lower threaded end of mandrel 12 is a normally fixed collar 25, and a pin 26 may be employed below this collar to prevent accidental loss thereof.
- In the mandrel 12, a short distance above 15 its lower end, is a transverse slot 27. In this slot, and pivoted on pin 28, are two dogs 29 having shoulders 29a at their upper ends. The upper ends of the two pivoted dogs are urged outwardly by a spring 30.
- 20 In operation, the parts are normally in the position shown in Fig. 1. Collar 15 is spaced slightly away from the shoulder at 11, so that upper slips 17 are almost, but not quite, in their uppermost positions, being 25 moved to this position by spring pushed pins 18. In this position, they are in a contacting non-biting engagement with a pipe when the spear is inserted. Lower slip carrying block 21 is elevated above end collar 25, but 30 is not quite in its uppermost position. Locking dogs 29 are accordingly held against outward movement. The lower slip block is held in this position by a thin stick of wood α shown in Fig. 1, which stick is disposed 35 between the block and end collar 25. Bottom slips 21 slide down, by gravity, to the position shown in Fig. 1, collar 25 preventing them from coming out.
- The spear, which has previously been attached to the drill string or cable, is lowered 40 into the casing. When it is desired to set the casing, a sudden upward jerk is applied to the cable, displacing or breaking stick α . Lower slip block 21 moves downwardly, by gravity, forcing bottom slips 23 outwardly. Collar 15 also moves down, together with upper slips 17. As slips 17 move 45 down, they ride out into pipe-engaging position.
- 50 Upon the cable then being pulled tight, upper slips 17 catch the casing for withdrawing it. As the strain on the cable increases, slips 17 are urged further downwardly and outwardly. Should it become 55 necessary to release the spear, pressure is applied downwardly on the body A.
- Lower slips 23, which are in pipe-engaging 60 position, resist downward movement, whereupon the mandrel 12 slides inside the lower slip block 21. As collar 15 rests against the top of block 21, the body also moves downward relatively to collar 15 and upper slips 17. When the body has moved 65 sufficiently far downward for slips 17 to be in retracted position and collar 15 is against

the shoulder 11, the lower end of block 21 will be above the shoulders 29a enabling the dogs to spread. As soon as the dogs have spread, the parts will be locked, with the upper lifting slips 17 in retracted position. 70 Upon pulling up on the cable to withdraw the spear, slips 23 will move downwardly out of pipe-engaging position.

It will thus be seen that, while comparatively simple in construction, and without 75 the employment of delicate mechanisms, and by the provision of two sets of slips, a positively acting spear is provided.

In order to provide for the escape of dirt, 80 channels or grooves 32 may be provided in shoulder 7, through which dirt may be forced when slips 17 move upwardly.

It sometimes happens in rotary drilling operations, that the drill stem will part, and the part of the stem in the hole will 85 have to be withdrawn by using a casing spear. Inasmuch as water and mud passes down the drill stem and up the hole, there will be a sediment which will collect around the lower end of the pipe and prevent it 90 being withdrawn.

The modification shown in Fig. 8 is a construction adapted for withdrawing a rotary 95 drill stem under such conditions. The construction is substantially identical with that hereinbefore described, with the exception of the locking dogs, and the same reference numerals have been employed, except as to this part of the structure.

The body A has a longitudinal bore a 100 passing therethrough from one end to the other. Instead of a transverse slot 27 being formed in the lower part of the mandrel, recesses 27' are formed. In each recess is a pivoted dog 29', similar to dogs 29 hereinbefore described. Each dog 29' is urged outwardly by a leaf spring 30'. Thus, the passage through the body is continuous, and water passed therethrough may not escape 105 until it reaches the lower end of the spear. 110

In use, the spear is carried at the lower end of a string of pipe. It is lowered into the well and entered into the broken drill stem, and set. After it is set, a large quantity 115 of water may be passed down the string of pipe and through the spear, into the lower part of the drill stem. Some of the water will, of course, escape around the spear, but much of it will flow down to the bit at the lower end of the stem, and loosen the sediment around the lower end of the drill stem.

Various changes and modifications may be made in the construction of the tool within the contemplation of my invention, and within the scope of the appended claims. 120

I claim:

1. A casing spear comprising a mandrel having slips slidable on the upper part thereof, a wedge member slidable on the mandrel 130

below the slips, lower slips in contact with the wedge member, said mandrel being recessed below the top of said wedge member, pivoted dogs in the recess having means 5 thereon for engaging the wedge member when it is in its uppermost position to prevent downward movement thereof, and resilient means for urging the dogs into wedge engaging position, said dogs normally being 10 confined by the wedge member when said wedge member is below the uppermost limit of movement, the top of said wedge member transmitting motion to said upper slips.

2. A casing spear comprising a mandrel 15 having slips slideable on the upper part thereof, a wedge member slideable on the mandrel below the slips, a ring slideable on the mandrel interposed between the wedge member and the upper slips, the upper slips being 20 connected with said ring, lower slips in contact with the wedge member, said mandrel being recessed below the top of said wedge member, pivoted dogs in the recess having means 25 thereon for engaging the wedge member when it is in its uppermost position to prevent downward movement thereof, and resilient means for urging the dogs into wedge engaging position, said dogs normally being confined by the wedge member when 30 said wedge member is below the uppermost limit of movement, the top of said wedge member transmitting motion to said upper slips through said ring.

3. A casing spear comprising a mandrel 35 having slips slideable on the upper part thereof, a wedge member slideable on the mandrel below the slips, lower slips in contact with the wedge member, said mandrel being recessed below the top of said wedge member, pivoted dogs in the recess having means 40 thereon for engaging the wedge member when it is in its uppermost position to prevent downward movement thereof, resilient means for urging the dogs into wedge 45 engaging position, said dogs normally being confined by the wedge member when said wedge member is below the uppermost limit of movement, the top of said wedge member transmitting motion to said upper slips, and 50 means for resiliently urging the wedge member below the uppermost limit of its movement.

4. A casing spear comprising a mandrel 55 having slips slideable on the upper part thereof, a wedge member slideable on the mandrel below the slips, a ring slideable on the mandrel interposed between the wedge member and the upper slips, the upper slips being 60 connected with said ring, lower slips in contact with the wedge member, said mandrel being recessed below the top of said wedge member, pivoted dogs in the recess having means 65 thereon for engaging the wedge member when it is in its uppermost position to prevent downward movement thereof, re-

silient means for urging the dogs into wedge engaging position, said dogs normally being confined by the wedge member when said wedge member is below the uppermost limit of movement, the top of said wedge member 70 transmitting motion to said upper slips through said ring, and resilient means engaging the ring for urging the ring downwardly to yieldably hold the wedge member out of its uppermost position. 75

5. A casing spear comprising a mandrel having upper slips slideable on the upper part thereof, a slideable wedge member on the mandrel below the slips, said mandrel having a pocket formed therein near its lower end, a dog pivoted in the pocket, a spring for urging the dog outward, said dog normally being confined by said slideable wedge member, lower slips engaging the slideable wedge member, said dog being adapted to project into position under the wedge member to hold said wedge member against lowering movement when it has been forced to its uppermost limit.

6. A casing spear comprising a mandrel 90 having upper slips slideable on the upper part thereof, a slideable wedge member on the mandrel below the slips, said mandrel having a pocket formed therein near its lower end, a dog pivoted in the pocket, a spring 95 for urging the dog outward, said dog normally being confined by said slideable wedge member, lower slips engaging the slideable wedge member, said dog being adapted to project into position under the wedge member 100 to hold said wedge member against lowering movement when it has been forced to its uppermost limit, a ring slideable on the mandrel interposed between the bottoms of the upper slips and the top of the wedge member, said upper slips and ring having an interlocking engagement, and a spring 105 pressed vertically movable plunger in the mandrel engaging the ring for urging it downward to hold said wedge member above 110 its uppermost limit of movement.

7. A casing spear comprising a mandrel having upper slips slideable on the upper part thereof, a slideable wedge member on the mandrel below the slips, said mandrel having a pocket formed therein near its lower end, a dog pivoted in the pocket, a spring for urging the dog outward, said dog normally being confined by said slideable wedge member, lower slips engaging the slideable wedge member, said dog being adapted to project into position under the wedge member to hold said wedge member against lowering movement when it has been forced to its uppermost limit, a ring slideable on the mandrel interposed between the bottoms of the upper slips and the top of the wedge member, said upper slips and ring having an interlocking engagement, a spring 115 pressed vertically movable plunger in the mandrel 120

125

130

- engaging the ring for urging it downward to hold said wedge member above its uppermost limit of movement, and temporary holding means for releasably holding the wedge against downward movement when it is below the uppermost limit of its movement.
8. A casing spear comprising a mandrel having upper slips slideable on the upper part thereof, a slideable wedge member on the mandrel below the slips, said mandrel having a pocket formed therein near its lower end, a dog pivoted in the pocket, a spring for urging the dog outward, said dog normally being confined by said slideable wedge member, lower slips engaging the slideable wedge member, said dog being adapted to project into position under the wedge member to hold said wedge member against lowering movement when it has been forced to its uppermost limit, a longitudinal passageway in the body, said recess being at one side of the passageway and out of communication therewith.
9. A casing spear comprising a body having upper and lower sets of slips movable vertically and laterally into and out of operative position, means slideable on the body connecting all the slips of the upper set, whereby they must move in unison, and vertically movable means on said body controlling the actuation of both pairs of slips.
10. A casing spear comprising a body having upper and lower sets of pipe engaging slips movable into and out of pipe-engaging position, a vertically movable block on said body controlling the actuation of said slips, and pivoted dogs in said body arranged to hold said block at its uppermost limit of movement when said block has been moved to such position.
11. A casing spear comprising a body having a set of vertically and laterally movable casing elevating slips thereon, said slips being retracted when in their uppermost position and expanded in when their lowermost position, and yieldable means for normally urging said slips downwardly away from their uppermost position into a partially expanded position, in which position they are adapted to contact with but not grip the walls of a casing when inserted therein.
12. A casing spear comprising a body having a set of vertically and laterally movable casing elevating slips thereon, said slips being fully retracted in their uppermost position and fully expanded in their lowermost position, means slideable on the body with which the slips are connected whereby they may move in unison, and yieldable means bearing against said connecting means for urging it downwardly to hold said slips in a partially expanded position.
13. A casing spear comprising a body having a reduced upper end portion, a middle portion of larger diameter, slip-engaging faces on said middle portion, a shoulder between said faces and said reduced portion, slips movable vertically over said faces, and grooves in said shoulder through which foreign matter may be forced upon upward movement of the slips.
14. A casing spear comprising a body having a reduced upper end, a middle portion of larger diameter, and a lower mandrel portion extending downwardly from the middle portion, slip-engaging faces on said middle portion inclined away from the longitudinal axis of the body downwardly, upper slips movable vertically over said faces, a ring slideable on the mandrel connecting the slips, a lower slip-carrying block slideable vertically on the mandrel below said ring, vertically and laterally movable lower slips thereon, an abutment on the mandrel confining the downward movement of the lower slips and block, and locking means in said mandrel adapted to be projected under said block to prevent its downward movement when the block has been moved a predetermined distance above the abutment.
15. A casing spear comprising a body having a reduced upper end, a middle portion of larger diameter, and a lower mandrel portion extending downwardly from the middle portion, slip-engaging faces on said middle portion inclined away from the longitudinal axis of the body downwardly, upper slips movable vertically over said faces, a ring slideable on the mandrel connecting the slips, a lower slip-carrying block slideable vertically on the mandrel below said ring and abutting against said ring, whereby said ring and block may move vertically in unison, vertically and laterally movable lower slips thereon, an abutment on the mandrel confining the downward movement of the lower slips and block, and locking means in said mandrel adapted to be projected under said block to prevent its downward movement when the block has been moved a predetermined distance above the abutment.

In testimony whereof I affix my signature.
BERT R. EMRICK.
